PLATE

John H. Reiser, Los Angeles, Calif., assignor to Wallace China Co., Ltd., Huntington Park,
Calif., a corporation of California

Application July 23, 1951, Serial No. 15,988

Term of patent 14 years

(Cl. D44—15)

To all whom it may concern:

Be it known that I, John H. Reiser, a citizen of the United States, residing at Los Angeles, county of Los Angeles, and State of California, have invented a new, original and ornamental Design for a Plate, of which the following is a specification, reference being had to the accompanying drawing, forming part thereof.

The sole figure is a plan view of a plate of conventional configuration, showing my new design. The dominant feature of the design resides in the ornamentation shown on the apron of the plate.

I claim:

The ornamental design for a plate, as shown and described.

JOHN H. REISER.
